UNITED STATES PATENT OFFICE

2,537,985

TUNABLE RESONANT CIRCUIT

Josiah J. Godbey, United States Navy

Application September 21, 1945. Serial No. 617,896

2 Claims. (Cl. 178—44)

(Granted under the act of March 3, 1883, as
amended April 30, 1928; 370 O. G. 757)

1

This invention relates to shorting devices for tuned transmission lines, and more particularly to an adjustable shorting device for a pair of transmission lines.

In certain types of high-frequency electronic apparatus, it is a practice to employ tuned transmission on lines as resonant circuits. For example, certain high-frequency oscillator circuits employ transmission lines to determine frequency of oscillation. In such cases, it may become desirable to provide some means for adjusting the resonant frequency of the transmission line. Heretofore, one method of accomplishing this has been to employ a shorting bar which extends between the transmission lines, and the ends of the bar are connected thereto, the shorting bar being moved longitudinally with respect to the transmission line by a rotatable lead screw. At ultra-high-frequencies, however, the lead screw introduces undesirable capacitive effects and in any event, it is difficult to provide a good electrical contact between the ends of the shorting bar and the transmission lines.

In accordance with one embodiment of this invention, an adjustable shorting device may be provided for shorting a pair of spaced, parallel transmission lines, comprising a pair of spaced, coaxially disposed, externally threaded discs, the peripheries of which engage the opposed, inner sides of the transmission lines, which are suitably threaded. A spring is mounted between the discs to urge them apart to cause their peripheries to engage tightly the threaded portions of the transmission lines while keying means are provided to cause the discs to rotate together as the position of the shorting device is adjusted longitudinally with respect to the transmission line.

Other objects and advantages of the present invention will be apparent from the following detailed description taken in conjunction with the drawings, wherein:

Fig. 1 is a plan view of a pair of spaced, parallel transmission lines having associated therewith a shorting device constructed in accordance with one embodiment of this invention;

Fig. 2 is an end view of the structure shown in Fig. 1; and

Fig. 3 is an enlarged, longitudinal vertical view of a portion of Fig. 1.

Referring now to the drawings, it will be seen that a pair of spaced, parallel transmission lines 5 have been provided, having a circular plate 6 mounted across the left end thereof, as viewed in Fig. 1, and being rigidly secured thereto serves to maintain the proper spacing between the left

2

portions of the transmission lines. The right ends of the transmission lines may be connected to a suitable electronic device (not shown), as is well known in the art. The resonant frequency of these transmission lines, and as the electrical length is decreased, the frequency at which the lines will be resonant is correspondingly increased.

In order to provide a simple and efficient shorting device whereby the electrical length of the transmission lines may be readily varied, in accordance with the present invention a pair of spaced, coaxially disposed, substantially parallel, externally threaded discs 7 and 8 are located between the transmission lines 5, the inner opposed sides of the transmission lines 5 being suitably threaded to receive and engage the threaded peripheries of the discs 7 and 8. Thus by rotating the discs 7 and 8 to cause them to travel to the right or to the left, as viewed in Fig. 1, the electrical length of the transmission line may be decreased or increased. Rotation of the discs is effected by inserting a screw driver, or other suitable device through an aperture 9 formed in the central portion of the mounting plate 6 and engaging the end thereof with a transversely extending slot 10, formed in the left face of the disc 7, as viewed in Figs. 1 and 3. In order to cause the disc 8 to rotate with the disc 7, a pair of keying or guide pins 11 are mounted on, or integrally formed with, the right side of the disc 7 and extend to the right therefrom into suitable apertures 12 formed in the left face of the disc 8. In assembling this shorting device on the transmission line 5, it will be understood that the desired spacing between the discs 7 and 8 may be readily obtained. It is usually desirable that the spacing between the discs be held to a minimum.

In order to assure a satisfactory electrical contact between the peripheries of the discs and the threaded sides of the transmission lines 5, and at the same time to increase the frictional engagement therebetween to prevent the shorting discs from changing position after being adjusted, a helically coiled spring 13 is located between the discs 7 and 8 and, the left end of the spring 13 extends into a shallow recess 14 formed in the right face of the disc 7 while the right end of the spring 13 extends into a similar recess 15 formed in the left face of the disc 8. The spring 13 urges the discs apart providing thereby a firm engagement of the peripheries of the discs with the threaded portions of the lines 5.

In the operation of this device, when it is desired to change the electrical length of the trans-

mission line 5, a screw driver is inserted through the aperture 9, and its end engaged with the slot 10 of the disc 7. The disc 7 is then rotated, thereby causing the disc 8 to rotate correspondingly and to move to the right or to the left, as viewed in Fig. 1, to decrease or increase the electrical length of the transmission line. The device of this invention, by reason of its compactness, provides a wider range of adjustment for a given size than is feasible with a shorting bar moved by a lead screw, and at the same time, by eliminating the need for a lead screw, eliminates the undesirable capacitive effects of the lead screw. Furthermore, the need for providing spring contacts at the ends of the shorting bars, as is the conventional practice, is avoided by virtue of the engaging pressure obtained by the use of the spacing spring 13.

While this invention has been described in conjunction with a pair of transmission lines, it will be understood that many other applications of this device are possible and that many changes and modifications may be made therein without departing from the spirit or scope of the present invention.

The invention shown and described herein may be manufactured or used by or for the Government of the United States of America for governmental purposes without the payment of any royalties thereon or therefor.

What is claimed is:

1. A distributed constant radio frequency adjustably tuneable circuit comprising a two conductor open transmission line section having a pair of straight rigid conductor members, means for maintaining the members in parallel spaced relationship, complementary thread means on the

adjacent sides of the members, and flat annular externally threaded shorting means diametrically engaged by and between the members for threadwise adjustable positioning along the line section.

- 5 2. A distributed constant radio frequency adjustably tuneable circuit comprising a two conductor open transmission line section having a pair of straight rigid conductor members, means
 10 for maintaining the members in parallel spaced relationship, complementary thread means on the adjacent sides of the members, and shorting means comprising a pair of flat annular externally threaded discs diametrically engaged by
 15 and between the members for threadwise adjustable positioning along the line section, biasing means interposed between the discs for maintaining frictional engagement with the threaded members, and means for causing the discs to rotate together.

20 JOSIAH J. GODEBEY.
